STUFFED TOY

Terrance R. Mitchell, 4611 N. Highway 8,
New Brighton, Minn.

Filed Oct. 9, 1964, Ser. No. 82,110

Term of patent 14 years

(Cl. D34—2)

FIG 1

FIG 6

FIG. 1 is a perspective view of a stuffed toy embodying my design;

FIG. 2 is a front elevational view of the same;

FIG. 3 is a side elevational view of the same;

FIG. 4 is a rear elevational view of the same;

FIG. 5 is a top plan view of the same; and

FIG. 6 is a bottom plan view of the same.

The side opposite that shown in FIG. 3 is substantially a mirror image of that shown.

I claim:

The ornamental design for a new stuffed toy, as shown and described.
